METHOD FOR BACKING OFF BROKEN STUDS

John Dean Hoover, Victorville, Calif.

Application July 6, 1951, Serial No. 235,408

2 Claims. (Cl. 29—401)

1

This invention relates to a method for backing off broken studs.

In the backing off of broken studs, as heretofore proposed, a single round hole is first drilled in an end of the broken stud, and then a round extractor is inserted in such hole and rotary movement applied to the inserted extractor to effect the backing off of the stud. A round extractor in a round hole does not afford the proper gripping action for the backing off of the broken stud.

An object of the present invention is to provide a method for backing off broken studs which enables the formation of a hole in the broken stud of a type such as to insure a positive and proper gripping with a conformably shaped extractor when inserted therein.

Another object of the present invention is to provide a method for backing off broken studs which is simple in execution, and is positive in action.

Other objects of the present invention will become apparent from the following description taken in conjunction with the accompanying drawing, in which:

Figure 1 is a fragmentary sectional view showing a broken stud in threaded engagement with a casing.

Figure 2 shows a centering punch in position upon the end of the broken stud for forming the discernible points which serve as drilling axes for the respective overlapping holes.

Figure 3 shows the drill centered upon one of the formed discernible points and ready to drill into the end of the broken stud.

Figure 4 shows the completed hole formed in the end of the broken stud as the result of the drilling of the overlapping holes about each of the discernible points as the drilling axis.

Figure 5 shows the extractor in position in the completed hole formed in the end of the broken stud.

Figure 6 shows the extractor carrying the broken stud backed off of the casing.

Referring to Figure 1, the numeral 10 designates a broken stud which is in threaded engagement with the casing 11. In backing off of such broken stud according to the method of the present invention there is formed simultaneously in an end of the broken stud three discernible points which are spaced equally from the center line of the stud and spaced from the perimeter of the stud. As shown in Figure 2, this formation is effected by placing a centering punch 12 which carries three centering points 13 spaced equally

2

from each other upon the end 14 of the stud 10 so that the centering points are equally distant from the center line of the stud, and then applying an impactive force to the end of the punch of a magnitude such as to simultaneously impress upon the end of the broken stud three discernible points 15, Figure 3, the latter points being likewise equally distant from each other and from the center line of the stud as well as being spaced from the perimeter of the stud.

With the completion of the three discernible points 15 on the end 14 of the stud 10, drilling in turn about each of such points as the drilling axis is caused to be done until three overlapping holes are formed of a depth to accommodate a conformably shaped extractor, the drilling being effected by means of a drill 16, Figure 3, whose radius is greater than the distance between each of the points 15 and the center line of the stud. Preferably, the drilling is effected by first centering the drill 16 on one of the points 15 and causing the drill to penetrate to a depth of not more than one sixteenth of an inch, then repeating the centering and penetration of the drill in turn upon the other two of the points 15, and these operations continued in turn upon the respective part formed holes until three overlapping holes of a depth sufficient to accommodate a conformably shaped extractor is attained. The resulting three overlapping holes form a single hole 17, Figure 4, which is in the shape of a cloverleaf. While drilling the three overlapping holes it is advisable to angle the bit of the drill 16 slightly away from the center line of the stud. By so doing the centers of the individual holes will be preserved and enable the holes to be drilled to any desired depth.

Inserted in the thus formed hole 17 of the stud 10 is an extractor 18, Figure 5, the extractor 40 having the end 19 conformably shaped to fit such hole. With the extractor thus inserted, rotary movement is applied to the extractor in a direction such and for a time sufficient to cause backing off of the broken stud 10 from the casing 11 as shown in Figure 6.

It is to be noted that since the drilled hole 17 is sufficiently large to accommodate the triangular or conformably shaped tip of the extractor 18 it is unnecessary to drive the extractor into the hole. Therefore, no outward pressure is applied to the stud, causing expansion of the stud in the threads. Should the extractor be broken off in the hole in the stud removal of the broken tip can be accomplished easily, permitting the immediate insertion of another extractor. Should

the broken stud in the casing prove too tight for the extractor there is nothing to interfere with the stud being drilled out completely and the hole retapped with an oversize thread.

I claim:

1. The method for backing off broken studs comprising forming simultaneously in an end of a broken stud three discernible points spaced equally from the center line of said stud and spaced from the perimeter of said stud, centering a drill whose radius is greater than the distance between each of said points and the center line of said stud upon one of said points, causing drilling of said drill about said one point as an axis to form part of a hole, centering said drill upon the other of said points, causing drilling of said drill about said other point as an axis to form a like part of another hole overlapping said first named hole, repeating the centering and drilling of said drill in turn upon said one and other points until completion of the formation of overlapping holes of a depth sufficient to accommodate a conformably shaped extractor, inserting an extractor which is conformably shaped to fit the thus formed holes into said overlapping holes, and applying to said extractor rotary movement in the direction such as to cause backing off of said broken stud.

2. The method for backing off broken studs comprising impressing simultaneously in an end

of a broken stud three discernible points spaced equally from the center line of said stud and spaced from the perimeter of the stud, drilling in turn about each of said points as an axis and with a drill whose radius is greater than the distance between each of said points and the center line of said stud to form overlapping holes of a depth sufficient to accommodate a conformably shaped extractor, inserting an extractor which is conformably shaped to fit the thus formed holes into said overlapping holes, and applying to said extractor rotary movement in a direction such and for a time sufficient to cause backing off of said broken stud.
